DESIGN FOR A WALKING CANE

Tommy Harvey Fletcher, Hollywood, Calif.

Application June 6, 1938, Serial No. 77,622

Term of patent 3½ years

To all whom it may concern:

Be it known that I, Tommy Harvey Fletcher, a citizen of the United States, residing at Hollywood, California, in the county of Los Angeles and State of California, have invented a new, original, and ornamental Design for a Walking Cane, of which the following is a specification, reference being had to the accompanying drawing, forming a part thereof.

Fig. 2 is a side elevational view looking from either the right or the left of Fig. 1.

Fig. 3 is a top plan view thereof.

I claim:

The ornamental design for a walking cane, as shown.

TOMMY HARVEY FLETCHER.
